UNITED STATES PATENT OFFICE

JOHN KARMAZIN, OF DETROIT, MICHIGAN

SERIES CONDENSER FOR REFRIGERANT COOLING

Application filed April 14, 1927. Serial No. 183,663.

This invention relates to heat exchange devices, and particularly to the type of heat exchange unit intended for the cooling of a fluid which has become heated by compression or 5 by contact with bodies at higher temperatures, such as parts of an internal combustion engine, refrigerating plant or the like.

One object of the invention is to provide a heat exchange unit comprising an elongated 10 but compactly arranged fluid conducting passage through the cooling unit.

A further object of the invention is to provide a pressure cooling unit or condenser of the fin and tube type in which the fluid under 15 pressure or compression to be cooled is conducted through a plurality of tubes arranged in series.

A further object of the invention is to provide a radiator cooling unit in which fluid 20 conducting tubes built up by superposing a plurality of fin elements having tube sections integral therewith are so connected that the fluid to be cooled, or a part thereof, traverses a plurality of the tubes in sequence, before being returned to the system with which the 25 cooling unit is connected.

A further object of the invention is to provide a cooling unit or section in which the fluid to be cooled is conducted through a path 30 of greater length than the length of the cooling unit, but within the cooling unit.

A further object of the invention is to provide a cooling unit with separate cooling 35 passages for the reception of two or more different fluids, usually associated with the same system or machine, such, for example, as the cooling water and the lubricating oil of an internal combustion engine.

With these and other objects in view, my 40 invention consists in the novel devices, combinations and arrangements of parts illustrated in the drawings and to be hereinafter more fully described.

In the drawings,

Fig. 1 is a fragmentary front elevation, 45 partly in section, of a radiator or condenser unit embodying the present invention.

Fig. 2 is a fragmentary end elevation of the 50 unit shown in Fig. 1, enlarged and having

certain walls broken away to show the details of its construction.

Fig. 3 is a fragmentary top plan view of the condenser shown in Fig. 1.

Fig. 4 is a fragmentary inverted plan view, 55 showing the bottom of the condenser shown in Fig. 1.

Fig. 5 is a fragmentary front elevation, partly in section, of the radiator of an internal combustion engine having one form of 60 the present invention applied thereto.

Fig. 6 is a fragmentary plan view with parts broken away.

Fig. 7 is a detail of a yoke used for connecting successive tubes in series.

The construction shown in Figs. 1 to 3 is especially adapted, though by no means limited, to use as a condenser for household refrigeration systems. Numeral 10 indicates cooling flanges or fins which have extending 70 from one side and preferably integral therewith a plurality of tapering tubular projections 11. The projections 11 are adapted to be nested within the projections on the next lower fin element 10 to form continuous tubes 75 12 extending vertically throughout the stack of superposed elements. This construction is described more in detail in my prior copending application Serial No. 641,850, filed May 28, 1923.

In one aspect, my present invention contemplates the adaptation of the fluid cooling unit described in my application above identified to systems requiring a large reduction 85 in the temperature of a comparatively small quantity of fluid. To this end means are provided for connecting the tubes in such a manner as to form one continuous, tortuous conduit of great length through the condenser. This means may take the form of 90 tubular yokes 13 and 14, adapted to connect the ends of adjacent tubes at the top and bottom of the cooling unit. For example, when the cooling unit comprises two rows of tubes 12, the yokes 13 at the top may extend diagonally, connecting each of the front row tubes 95 with the back row tube of the next adjacent pair, (Fig. 3); while the yokes 14 at the bottom may extend transversely, connecting the front and back tubes of each pair (Fig. 4). 100

Thus a single continuous conduit is formed comprising the nested projections 11 and the yokes 13 and 14 extending from the intake pipe 15 to the outlet pipe 16. The bottoms 5 of the tubes 11 may be provided with integral baffle walls 10^a with protruding wings 10^b dividing the passage into two portions as described in my Patent No. 1,591,323 granted July 6, 1926.

10 The telescoping joints between the tube sections may if desired be secured by solder which may be applied in powdered form, with a flux, before the tubes are superposed, and subsequently heated to fusion, or the assembled cooling unit may be solder dipped. A cooling unit constructed in this manner is especially adapted for use as a condenser for household refrigeration machines, the intake and outlet pipes 15 and 16, being connected 20 into the cooling fluid containing system.

In Figs. 5 and 6, I have illustrated an application of the invention to the cooling of the lubricating oil of an internal combustion engine. In the device illustrated the oil cooling 25 radiator is built into the water cooling radiator. The water cooling radiator comprises fins 10 and tubes 17, formed integral with the fins 10 and nested together as illustrated in more detail in Fig. 2, which tubes 30 open into an upper header 18 and a lower header 19 of a conventional automobile radiator, connected in the usual way with the engine cooling system. A suitable number of the tubes 17 are connected at their upper and 35 lower ends by means of yokes 20 similar to the yokes already described, to form a single continuous conduit, said yokes 20 lying within the headers 18 and 19. The ends of the conduit are connected through pipes or tubes 21 40 and 22 with the engine lubricating system. The radiator cooling section may be built up of superposed fin and tube section elements, in the manner described in my prior application above identified. An effective oil cooling 45 device in an appropriate and convenient location is thus insured.

The refrigerating condenser illustrated in Figs. 1 to 4 is adapted to receive the refrigerating fluid under high pressure from the 50 compressor and because of the integral connection of the cooling fins 10 with the tube walls 11 to rapidly extract the heat from the compressed fluid providing a condenser unit of utmost strength and efficiency with a minimum size.

55 While I have illustrated and described in some detail certain typical embodiments of my invention these embodiments are to be considered as illustrative, and not restrictive, the 60 invention being limited only by a broad interpretation of the appended claims.

What I claim as my invention is:

65 1. A condenser for refrigeration machines comprising a plurality of superposed sheet metal fin elements each having integral tubu-

lar projections in parallel spaced relation extending transversely from one side thereof, the tubular projections on one element being nested within the juxtaposed element to form a plurality of continuous tubes, and one piece 70 yokes connecting the ends of said tubes to form a continuous conduit, and means for connecting the ends of said conduit into the fluid containing system.

2. A heat exchange unit of the integral fin and tube type comprising a plurality of fluid-passages formed of nested tubular projections having fin members integral therewith, the center of said passages being unobstructed except for relatively narrow integral heat 75 conducting bars across the center of the water columns at the ends of said projections and means at the end of said fluid passage for connecting the end of one passage to the end of an adjacent passage to cause the fluid to flow 80 85 in a continuous passage therethrough.

In testimony whereof I have affixed my signature to this specification.

JOHN KARMAZIN.
